UNITED STATES PATENT OFFICE.

ALONZO McMANUS, OF NEW BRITAIN, CONNECTICUT, ASSIGNOR TO NORTH & JUDD MANUFACTURING COMPANY, OF SAME PLACE.

IMPROVEMENT IN SNAP-HOOKS.

Specification forming part of Letters Patent No. **58,350**, dated September 25, 1866.

To all whom it may concern:

Be it known that I, ALONZO McMANUS, of New Britain, Hartford county, and State of Connecticut, have invented a certain new and useful Improvement in Snap-Hooks; and I do hereby declare the following description and accompanying drawings are sufficient to enable any person skilled in the art or science to which it most nearly appertains to make and use my said invention or improvement without further invention or experiment.

The nature of my invention and improvement consists in countersinking or constructing the shank of the hook with a recess for the reception of the end of the spring therein, and combining therewith a solid bridge arranged transversely thereover for the retention of the spring therein by means of the center of the bridge thereof being forced down thereon by the tap of a hammer.

Figure 1 is a view of the hook, showing the manner of attaching the spring to the inner face of the shank of the same and the means by which it is held thereto; Fig. 2, a longitudinal sectional view of the hook as indicated by the line *x y* in Fig. 1.

Like letters in both figures of the drawings indicate like parts.

The hook is represented by the letter A, the spring by the letter B. On the inner face of the shank of the hook—the point at which the spring is usually attached—a recess or depression, *a*, in the casting of the hook is made therein, (see Fig. 2,) sufficient in depth and width to receive the larger end of the spring, (see Fig. 1,) the recess beginning a little in the rear of the slot *b* through the shank, and extending a little forward of the same, with a slight inclination to the surface of the shank, so that the spring may be suitably adapted thereto. In the casting of the hook, also, and

at the same time, a bridge, *c*, is formed transversely and centrally over the slot, the ends of the bridge being cast with the face side of the shank.

The tapering end of the spring is introduced under the bridge from the rear side thereof, and brought out at the forward part of the same until the larger end of the spring slips into the recess, when, by the slight tap of a hammer on the top of the bridge, in the center thereof, it is depressed down firmly onto the spring, which is thus held and rigidly retained in the recess by the bridge.

The tapering end of the spring may be introduced through the slot from the outer side of the shank forward of the bridge, and the larger end of the same slipped back under the bridge into the recess, and then fastened.

It will be observed that the sides of the recess prevent any lateral movement of the spring or any possible chance of its slipping to the rear.

If the spring breaks or becomes weak from usage, by means of a punch inserted in the slot on the outer side of the shank onto the back side of the spring, and with a hammer, the bridge may be elevated to its original position, so that the spring may be taken out and a new one substituted in lieu thereof.

Having thus fully described my invention, what I claim as new, and desire to secure by Letters Patent, is—

Constructing the recess *a*, and combining therewith the solid bridge *c*, arranged transversely over the spring *B*, in connection with the slot *b*, substantially in the manner and for the purpose as herein described.

ALONZO McMANUS.
